COMBINED PORTABLE TAPE RECORDER AND SPEAKERS

Orville W. Larson, Skokie, Ill., assignor to Ampex
Corporation, Redwood City, Calif., a corporation of
California

Filed July 30, 1968, Ser. No. 12,965

Term of patent 14 years

Int. Cl. D14—01

U.S. Cl. D26—14

FIG.1

FIG.2

FIG.3

FIG.4

FIGURE 1 is a front perspective view of a combined portable tape recorder in accordance with my design;

FIGURE 2 is a rear perspective view of the combined portable tape recorder of FIGURE 1 with speakers superposed and inserted into the tape recorder;

FIGURE 3 is a front perspective view of the combined portable tape recorder of FIGURE 1 with the speakers removed and disposed at the sides of the tape recorder; and

FIGURE 4 is a rear perspective view of the combined portable tape recorder and speakers of FIGURE 3.

The dominant features of my design reside in the portions shown in solid lines.

I claim:

The ornamental design for a combined portable tape recorder and speakers, substantially as shown and described.
